HANDLE LINE SPORT FISHING REEL

Richard K. Sutz, 5800 Arlington Ave.,
Riverdale, N.Y. 10471

Filed Nov. 27, 1968, Ser. No. 14,694

Term of patent 14 years

Int. Cl. D22—06

U.S. Cl. D22—25

FIG. 1

FIG. 3

FIG. 2

FIG. 4

FIG. 5

FIG. 6

FIG. 1 is a perspective view of a handline sport fishing reel, showing top, end and one side of the reel.

FIG. 2 is a perspective view showing top, other end and other side of the reel.

FIG. 3 is a reduced side view of the reel.

FIG. 4 is a bottom plan view of the reel.

FIG. 5 and FIG. 6 are end elevational views of the reel.

For convenience in illustration, portions of a loop cord, fishing line, fishing hook, and sinker have been omitted from FIGS. 4, 5 and 6.

I claim:

The ornamental design for a handline sport fishing reel, as shown and described.
